CLAIM

The ornamental design for a literature organizer, as shown and described.

DESCRIPTION

FIG. 1 is a front elevational view of a literature organizer showing my new design;

FIG. 2 is a rear elevational view;

FIG. 3 is a right side elevational view, the left side being a mirror image thereof;

FIG. 4 is a top plan view;

FIG. 5 is a bottom plan view; and,

FIG. 6 is a top, right front perspective view thereof drawn to a reduced scale.

FIG. 1

FIG. 2

FIG. 3

FIG. 4

FIG. 5

FIG. 6
